SHIRT COLLAR SUPPORT

William W. McFall, River Forest, and Fred O. Kestner, Chicago, Ill.

Application November 9, 1945, Serial No. 627,699

2 Claims. (Cl. 223—83)

1

This invention relates to a novel and improved collar support for shirts to be used in packaging of same for delivery.

It is an object of the invention to provide a simple, inexpensive device adapted to be associated with the collar of a man's collar-attached shirt to sustain the neckband and collar tabs in proper position, which is strongly resistant to crushing or distortion by reason of a novel, three-ply construction thereof.

Yet another object is to provide a collar protective support of the type described, which is readily applied to a shirt for the purposes noted and which has an exposed area of substantial size adapted for the reception of advertising material or other notation.

The foregoing statements are indicative in a general way of the nature of the invention, but other and more specific objects will be apparent to those skilled in the art upon a full understanding of the construction and operation of the device.

One embodiment of the invention is presented herein for the purpose of exemplification, but it will be appreciated that the invention is susceptible of incorporation in other modified forms coming equally within the scope of the appended claims.

In the drawing,

Fig. 1 is a plan view of a stamped out and printed blank from which the support of the invention is set up and applied;

Fig. 2 is a plan view illustrating the support in operative position relative to a shirt neckband and collar; and

Fig. 3 is an enlarged view in section on a line generally corresponding to line 3—3 of Fig. 2.

Referring to the drawing, the reference numeral 10 generally designates a blank of an appropriate, inexpensive grade of flexible paper board or cardboard. This blank is die-cut, creased and slitted to provide a pair of flat, angularly disposed, divergent arms 11 connected to one another by a central yoke portion 12 of lesser width and a medial transverse extension 13 bendably connected to the yoke portion 12 along a scored or creased hinge or fold line 14. A pair of angled slits 15 terminating at the extremities of the fold line 14 serve to define shoulders 16 at the junction of arms 11 and yoke 12 and to likewise define lateral wings 17 on the extension 13. The extension 13 is further subdivided by a pair of angular slits 18 and a connecting scored or creased fold line 19 to provide a terminal spring member, designated 13', of the same width as the

2

intermediate portion between fold lines 14, 19, designated 13'' for identification. The slits 18, it will be noted, serve to define flexible wings 20 at either side of said terminal portion.

- 5 In use, the blank is folded twice, i. e., consecutively on fold lines 14 and 19, to produce a triple-ply construction. The respective divergent arms 11, along with adjacent flexible wings 20 of the terminal portion 13', are then inserted in 10 opposite directions beneath the respective outer collar tabs 21 of the shirt, i. e., between said flaps and the neckband 22. The lateral wings bear against and flexibly sustain said divergent arms 11, maintaining the same outwardly against the 15 collar tabs, while the intermediate portion lies forwardly of the so inserted portions, with its wings 17 externally overlying the collar tabs to hold the same downwardly in proper position, and maintaining a stressed condition in arms 11 and 20 wings 20. The three-ply construction resulting from the above provisions serves effectively to resist crushing forces on the collar.

We are aware that various types of collar supporting structures have heretofore been evolved, 25 but we believe that none thereof possesses the advantageous features inherent in that described above.

In operative condition, the terminal reinforcing element 13' extends approximately vertical 30 and parallel to the upstanding neckband of the freshly pressed shirt, thus enhancing the spring action of the wings 20 thereon on the arms 11. As distinguished from this, the intermediate portion 13'' and yoke 12 with its arms 11 tend to lie 35 in a plane generally paralleling the outwardly flared plane of the collar tabs. Hence, a spring binding and expanding action results which is very effective for the above purposes, and which also serves to resist inadvertent displacement of 40 the article from operative position.

The intermediate portion is well adapted for having imprinted thereon the representation of 45 a bow tie, along with other advertising material or notation, which adds considerably in the way of attractiveness and eye appeal to the final article.

We claim:

1. A collar support of the type described, comprising a blank of flexible fibrous material slitted to provide a main collar sustaining yoke having 50 angularly extending arms integral therewith, an intermediate portion of substantial width bendably connected to said yoke, and a terminal portion bendably connected to said intermediate portion, said intermediate and terminal portions

each having a pair of opposed wings extending laterally in the general direction of said arms, said intermediate and terminal portions being successively foldable around said yoke into position adjacent the respective opposite sides thereof, said arms and terminal portion wings being insertable between the neckband and collar tabs of a shirt, with said last named wings in flexible sustaining engagement behind the respective arms, said intermediate portion and wings thereof externally overlying the collar tabs to restrain the same and presenting a substantial forward area for the reception of printed matter.

2. A collar support of the type described, com-

prising a blank of flexible fibrous material cut to provide three hingedly connected portions each having a pair of laterally extending arm-like members, said portions being foldable into substantially parallel position and the members of two thereof being insertable between the neckband and collar tabs of a shirt, with the members of one in flexible sustaining engagement with those of the other, the third portion and members thereof externally overlying the collar tabs to restrain the same downwardly.
